[57] CLAIM

The ornamental design for a device for moving a writing instrument in a repetitive pattern, substantially as shown and described.

DESCRIPTION

FIG. 1 is a left side elevational view of a device for moving a writing instrument in a repetitive pattern showing my new design;

FIG. 2 is a front elevational view thereof;

FIG. 3 is a right side elevational view thereof;

FIG. 4 is a top-plan view thereof;

FIG. 5 is a rear elevational view thereof.

The bottom surface is plain and unornamented except for the support members seen in FIGS. 1, 2, 3 and 5.

FIG. 1.

FIG. 2.

FIG. 4.

FIG. 3.

FIG. 5
